UNITED STATES PATENT OFFICE.

WALTER M. CROSS, OF KANSAS CITY, MISSOURI, ASSIGNOR TO GASOLINE PRODUCTS COMPANY, OF NEW YORK, N. Y., A CORPORATION OF NEW YORK.

PROCESS FOR TREATING PETROLEUM HYDROCARBONS.

Application filed August 13, 1924. Serial No. 731,749.

This invention relates to improvements in a process for treating petroleum hydrocarbons, and refers more particularly to a process in which petroleum oils are converted 5 from oils of a relatively high boiling point to oils of a lower boiling point and having the characteristics of gasoline and the like.

This invention is a modification of an invention disclosed in a prior application, 10 Serial No. 701,283, filed March 24, 1924.

Among the salient objects of the invention are, to provide a process in which the oil undergoing conversion is subjected to temperature and pressure conditions regulated to effect the conversion while the oil 15 is maintained substantially in the liquid phase; to provide a process in which the oil is preferably treated continuously, but converted from the charging stock to what is 20 termed as a synthetic crude containing increased quantities of low boiling point hydrocarbons relative to the low boiling point fractions contained in the original charging stock; to provide a process in which the hot 25 synthetic crude is introduced to a stage of reduced pressure while in a highly heated condition whereby the lighter fractions are immediately distilled off due to the contained heat in the oil; to provide a process 30 in which water vapors or steam, preferably in a superheated condition, are introduced or injected in the oil either in the distillation stage or as they enter the distillation stage 35 whereby vaporization is promoted and a sweeter product results.

The single figure is a diagrammatic side elevational view of the apparatus with parts shown in section.

Referring to the drawing, at 1 is shown a 40 furnace in the upper part of which is positioned a preheating coil 2 and in the lower portion a second bank of tubes comprising a second heating coil 3. These banks of tubes are connected by a transfer line 4. 45 The furnace is preferably heated by means of gas burners not shown, the combustion gases passing upward around the tubes and passing off through the stack 5. Six (6) is a reaction chamber connected by a transfer line 7 to the discharge end of the lower 50 bank of tubes. An evaporator is shown at 8 connected by a vapor line 9 to the refluxing tower 10 which is preferably of the bubble tower type, while a liquid transfer line 11 connects the evaporator with the re-

action chamber 6. A reducing valve 12 is interposed in the line 11, while a steam line 13 regulated by a valve 14 is interposed between the valve 12 and the evaporator 8, furnishing a means for introducing steam 60 to the oil as it is discharged from the reaction chamber into the evaporating stage. Fifteen (15) is a water cooled condenser. Sixteen (16) is a gas separator, while the tanks 17, 18, and 19 furnish storage means 65 for gasoline, recharging stock and residual bottoms or fuel oil respectively. A tank 20 is interposed in a drawoff line 21 from the refluxing tower 10.

The process is similar in operation to that 70 explained in some of my previous applications, and particularly in my application Serial No. 629,723, filed April 3, 1923, and Serial No. 701,283 filed March 24, 1924. It differs, however, from the latter case in that 75 instead of introducing or injecting a blending oil into the transfer line I prefer to introduce at this point, or into the evaporating tower directly, a jet of superheated steam.

Describing briefly the process operated, 80 oil is introduced from the charging tank 18 through the line 22 and forced by means of the pump 23 through the upper preheating coil 2 and lower heating coil 3 in the furnace 1. After passing through the lower 85 coil, the oil has been sufficiently heated to be in the state of incipient conversion, that is, the oil has been sufficiently heated to bring it to a cracking temperature while it has not had sufficient time for the conversion 90 to be consummated. In this state, while the oil is at a cracking temperature, substantial conversion has not taken place as this condition would be accompanied by the separation and deposition of considerable 95 quantities of free carbon. In operating the process it is endeavored to eliminate this deposition of carbon in the heating tubes while at the same time supplying sufficient heat to the oil to cause the conversion to be 100 completed in the reaction chamber 6 to which it is passed through the line 7.

In the reaction chamber the highly heated oil is collected in a considerable body and moves slowly therethrough allowing sufficient time factor for the cracking reaction to be completed therein. As stated, the pressure and temperature conditions are so regulated that the oil preferably is converted while being maintained substantially 110

in the liquid phase, pressure being imposed by the generated gases given off during the heating and conversion reaction.

The cracking product which I choose to term as synthetic crude containing an increased amount of low boiling point fractions which may be easily distilled off from the liquid body, is withdrawn through the line 11 and passed directly into the evaporation tower 8 through a pressure reducing valve 12. With the reduction of pressure and due to the contained heat of the oil, immediately on introduction to the tower there is distilled off from the oil body a substantial portion thereof in the form of light volatile fractions which rise through the top of the tower into the line 9 and are introduced into the bottom of the dephlemating or refluxing tower 10. The unvaporized products collect in the bottom of the evaporator and are withdrawn automatically by the manipulation of the valve 24 functioned by means of a liquid level regulating device diagrammatically shown at 25. These bottoms are passed through the drawoff line 26 to a cooling coil 27 positioned in the condenser box 15 and are passed thence through the line 28 to the fuel oil storage tank 19.

The overhead material introduced into the bottom of the bubble tower rises therethrough, percolating through a series of liquid oil pools which serve to separate out the higher boiling point fractions. The particular construction of this bubble tower forms no part of the present invention, as it is well known in the art.

The incondensable portion of the vapors reaching the top of the bubble tower or refluxing column pass off through the vapor line 29 and are subjected to a condensing action in a coil diagrammatically shown at 30 in the condenser box 15. The liquid distillate condensed from these vapors is collected in a gas separator 16 from which the liquid distillate is removed through a line 31 controlled by a valve 32 and directed to the gasoline storage tank 17 while the gases pass off through the pipe 33 controlled by a valve 34 and may be utilized as fuel in the furnace during operation or for other fuel purposes. It may, if desired, be treated for certain light fractions that were not separated out in the gas separator, as this gas is of a relatively rich character.

The reflux condensate, separated out in the bubble tower which is gravitated downwardly and in an opposite direction of the vapors, collects in the bottom of the tower and is automatically drawn off from time to time through the valve 35 automatically functioned by means of the liquid level regulating device 36 identical in its operation to that shown at 25. A valve 37, interposed in the drawoff line 38, furnishes a means for directing the condensate through

a cooling coil 39 in the condenser box and thence through the line 40 to the recharging stock storage tank. A second valve 41, interposed in the line 21, when manipulated in connection with the valve 37 may be utilized to short-circuit the condensate directly to the reflux tank 20 whereby it may be recycled directly to the cracking unit through a pipe 42 controlled by a valve 43, this pipe having communication directly with the charging line 22 which communicates with the suction side of the charging pump 23.

The process is designed for continuous operation, the oil being introduced to the heating unit from the charging stock tank while selected portions of the refluxed material is recycled if desired.

Into the transfer line through the pipe 13 or directly into the bottom of the evaporator, if desired, is injected quantities of superheated steam for the purpose of promoting the distillation of the oil in the evaporator, driving off from the oil body a sweeter product than would result from distillation due solely from the heat contained in the oil.

The advantages of steam distillation are well known in the art, in producing a high quality and sweeter distillate than that obtained by direct heating. It is thought to be novel, however, to crack the oil in a liquid phase and utilize the contained heat by distilling off the lighter fractions and during this distillation injecting superheated steam to the oil body in order to promote the evolution of vapors from the oil body and improve the character of the final product. A further advantage of the introduction of steam at this point is to give the residual bottom unvaporized in the tower a higher degree of fluidity than would normally result from distillation with the introduction of steam. By thus increasing the fluidity of the bottom, it is made more marketable, is easier handled due to the fact that it may be more readily pumped through pipe lines and, further, the amount of free carbon contained therein is considerably lessened.

I claim as my invention:

A process for treating petroleum hydrocarbons comprising raising the oil to a cracking temperature in a heating stage, collecting all the oil to be treated in a reaction stage while maintaining temperature and pressure conditions adapted to effect conversion while the oil is substantially in the liquid phase, withdrawing all the conversion products from the reaction stage in a relatively small stream, releasing the pressure on the stream and injecting steam into the flowing stream, admitting the mixture of oil and steam to an enlarged zone maintained at reduced pressure to distill off the lighter fractions of the converted products.

WALTER M. CROSS,
